UNITED STATES PATENT OFFICE

1,977,287

TRIPPING MECHANISM FOR EXCAVATING MACHINES

Gustaf H. Olson and Hilmer N. Ekbom, Chicago, Ill., assignors to Link-Belt Company, Chicago, Ill., a corporation of Illinois

Application July 29, 1932, Serial No. 625,805

10 Claims. (Cl. 214—146)

Our invention relates to improvements in tripping mechanisms for excavating machines and has for one object to provide a new and improved form of tripping mechanism used in connection with a latch or door lever used in connection with the bottom dump or door of a power shovel, dipper scoop or bucket.

One object of this invention is to provide a power means for tripping the door latch to dump the load of the bucket, scoop or dipper. Another object is to provide power means for this purpose wherein the application of power is controlled by the operator and released automatically after the latch has been tripped. Another object of this invention is to provide an automatic trip cable rope or slack take up independent of the rotation of the shipper shaft.

In general we use a driving rotatable member secured to a power shaft driven by the excavator's power plant; a driven member rotatable in relation to the power shaft and having an eccentric portion directly connected to the latch; an engaging member which connects and disconnects the driving and driven members; a trigger member which operates the engaging member in one direction at the will of the operator to connect the driving and driven members and which automatically operates the engaging member in the opposite direction independent of control of the operator to disconnect the driving and driven members and a braking member acting on the driven member whose purpose is to prevent over-running of the driven member in its cycle.

In order to provide take up for the trip cable or rope we use a take up drum rotatably mounted on or at the axis of the shipper shaft, a toothed pinion mounted independent of the shipper shaft and meshing with the toothed rack on the dipper handle, a connecting means between such pinion and the take up drum comprising a gear train, a chain drive or a belt drive or any combination thereof arranged to give such direction of rotation to the take up drum that relative motion between rack and pinion will rotate the take up drum and thereby take up the trip cable or rope so as to keep it constantly taut independent of the position of the dipper handle.

Our invention is illustrated more or less diagrammatically in the accompanying drawings, wherein—

Figure 1 is a side elevation of a power shovel; Figure 2 is a plan view of the power operated

Figure 3 is a side view of the mechanism shown in Figure 2;

Figure 4 is a longitudinal section through the center of the power shaft showing the mechanisms associated with it;

Figure 5 is a side view of the slack cable take up using a gear train;

Figure 6 is a bottom plan view of Figure 5;

Figure 7 is a side view of a slack take up with chain drive;

Figure 8 is a bottom plan view of Figure 7;

Figure 9 is a side view of a slack take up device using the cable as a connecting means;

Figure 10 is a bottom plan view of Figure 9;

Figure 11 is a section along the line 11—11 of Figure 2.

Like parts are indicated by like characters throughout the specification and drawings.

Referring first to Figure 1, A indicates a suitable crawler tread running gear supporting a frame A¹ on which is mounted a combination gear ring and roller path A² which carries a rotating platform A³ counterbalanced at A⁴ having a mast A⁵ projecting upwardly therefrom, the mast being held in position by means of stays A⁶, the boom A⁶ being held in angular position with respect to the mast and the platform by cables A⁷. A⁸ is a dipper handle slidable in the yoke A¹⁰ which yoke is pivoted on the boom. At the end of the dipper handle is the dipper bucket A¹¹ having the pivoted door or bottom dump A¹². A¹³ is a cable extending over sheaves A¹⁴ associated with the dipper bucket A¹¹, sheave A¹⁵ on the end of the boom A⁶, to the hoisting drum A¹⁷.

On the underside of the dipper handle A⁸ is a rack B, engaged by a driving pinion B¹ on the shipper shaft B² which shipper shaft is adapted to be rotated by an engine B³, or by any other suitable power source, to give back and forth motion to the dipper handle. B⁴ is a latch adapted to hold the door or bottom dump in the locked position. B⁵ is a chain extending from the latch over the sheave B⁶ to the latch lever B⁷. B⁸ is a trip cable extending from the latch lever B⁷ over the sheave B⁹ concentric with the shipper shaft, thence over a sheave B¹⁰ on the lever B¹¹ pivoted on the boom A⁶, thence to an anchorage on the take up drum B¹² on the shipper shaft B².

The take up drum B¹² is associated with a gear B¹³ in mesh with an idler pinion B¹⁴, which in turn is in mesh with a pinion B¹⁵, which pinion is on a shaft B¹⁶ in the bracket B¹⁷. This shaft carries a gear B¹⁸ in mesh with the rack B on the dipper handle so that longitudinal move-

ment of the rack will cause rotation of the take up drum B^{12} in such direction and at such rate as to keep the trip cable B^8 taut for all positions of the dipper handle. As the trip cable is drawn in or paid out by the rotation of the take up drum, it always passes out over the sheave B^{10} on the lever B^{11} , thence over the sheave B^9 and thence out along the dipper handle.

10 C is a tripper power cable leading from one end of the lever B^{11} under the sheave C^1 concentric with the pivot axis of the boom, thence up over a sheave C^2 , thence over a sheave C^3 , thence up to an anchor C^4 on the mast A^5 . A pull on this cable C will rock the lever B^{11} and exert a pull on the trip cable B^8 to rock the latch lever B^7 and exert a tension on the chain B^5 and release the door latch B^4 .

15 Referring now to Figures 2 and 3, D is a power shaft. D^1 is a driving member mounted on the stub shaft D^2 which is threaded in and held against rotation with respect to the driving shaft D. D^3 is a driven member rotatably mounted on the stub shaft D^2 having an eccentric pin D^4 on which the sheave C^3 is rotatably mounted. D^5 is an engaging member slidably mounted in the driven member D^3 . This engaging member is yieldingly pressed to the left in Figure 4 by the spring D^6 which abuts at its other end on the cover plate D^7 held in position on the driven member D^3 by means of the screws D^8 . D^9 is a trigger pivoted at D^{10} having a working lever D^{11} to the free end of which is connected the hand rope D^{12} , the other end of the hand rope being anchored at D^{13} .

20 35 The trigger has a cam portion E which rides in the groove E^1 in the driven member D^3 and locks with a notch E^2 in the engaging member D^5 to hold it in position against the urge of the spring D^6 with its driving jaw E^3 out of engagement with the driving member D^1 . When the operator pulls on the hand rope D^{12} to rock the latch and lever about the pivot pin D^{10} , this cam member E is withdrawn from the engaging member D^5 , the spring D^6 pushes it to the left and causes the jaw E^3 to engage the aperture E^4 in the driving member D^1 thereby locking the driving member D^1 and the driven member D^3 and causing rotation of the eccentric pin D^4 about the center of rotation of the shaft D, thereby 25 exerting a tension on the cable C and so rocking the lever B^{11} and causing the latch to be disengaged. The cam member E has an inclined cam surface E^5 . The relation of the parts is such that the member D^5 never moves far enough to the left to cause the notch E^2 to be masked by the driven member D^3 so that when the operator has pulled the rope D^{12} to release the cam, the spring E^6 holds the cam against the driven member D^3 so that near the end of the cycle the cam surface E^5 will engage the notch E^2 in the member D^5 and draw the member D^5 back out of engagement with the driving member D^1 , thereby effecting an automatic release of the tension 30 on the rope C, so that all that the operator has to do is to pull once on the rope D^{12} , the power mechanism releases the latch and the parts automatically go back into the starting position ready for the next manipulation by the operator. In order to keep the driven member D^3 from overrunning, it is associated with an adjustable band brake E^7 , the pressure applied by the brake being controlled by the spring E^8 whose tension is adjustable by means of the nuts E^9 to whatever 35 tension is necessary to insure a stoppage of the

driven member as soon as the cycle has been completed.

40 If desired, instead of using the gear train B^{14} B^{19} B^{13} , it may be desirable to transmit the power as shown in Figures 7 and 8 by means of a sprocket chain F associated with a sprocket F^1 on the shaft B^{15} and with a sprocket F^2 associated with the take up drum.

45 50 If we are dealing with a machine wherein a rack is not used or wherein it is not convenient to take the power for the take up drum from the rack, the take up drum is operated by means of a cable F^3 anchored at each end on the dipper handle, winding about a drum F^4 associated with the take up drum B^{12} . Under such circumstances longitudinal movement of the dipper handle will cause the desired rotation of the take up drum.

55 60 In connection with shovels of the type known as independent crowd shovels where the teeth from that portion of the rack immediately adjacent the stop F^5 are omitted to permit rotation of the shipper shaft without movement of the dipper handle, clearly it is necessary that the take up drum be operated not by the shipper shaft but by some connection with the dipper handle either in connection where power is applied to the rack or the rope as indicated. If, however, the dipper handle is so arranged that movement of the shipper shaft always results in movement of the dipper handle, it might under some circumstances be desirable to omit the chain or gear train drive or the take up drum and key the take up drum direct to the shipper shaft, under which circumstances, movement of the shipper shaft would directly rotate the take up drum.

65 70 While we have shown a power pulley, obviously a sheave or drum around which the cable could be wrapped would work equally well and the same is true of a chain and sprocket combination. The same is true of a latch operating mechanism. A chain which could pass around the pulleys or a chain and sprockets or if desired, merely connecting links, could be used, and where in the specification and claims we have 75 called for a cable and pulley, it will be understood that we are using this language in its broadest sense as applied to any flexible supporting mechanism and any rotary applying power mechanism associated therewith. Also it 80 will be noted that the automatic trip device while illustrated as applied to booms and shovels having a dipper stick might equally well be applied to skimmer scoops and other devices which may be operated without the dipper stick where the 85 bucket travels parallel with or along the boom, and the same thing would apply to such devices as the trench hoe, in which case, it would be only necessary to run the cable connecting the drum and the latch along the boom over a sheave, 90 bell crank, etc., to provide automatic operation of the latch.

95 A¹⁸ indicates diagrammatically the excavating machine power plant.

100 We claim:

105 1. In combination, a boom, a dipper handle on the boom mounted for longitudinal reciprocation through an axis of angular displacement, a movable member on the dipper handle, a cable extending from the movable member to the center 110 of rotation of the dipper handle and cable take up means for drawing in and paying out the cable in consonance with the longitudinal displacement of the dipper handle, the cable take up means comprising a take up drum upon 115
